UNITED STATES PATENT OFFICE.

JOSIAH H. ROHRER, OF PHILADELPHIA, PENNSYLVANIA.

WATER-TUBE BOILER.

Application filed April 2, 1928. Serial No. 629,332.

My invention relates to boilers of the water-tube type and particularly to the providing of such boilers with a feed-water heater so constructed and arranged that the deleterious or corrosive gases, contained in the feed-water and liberated therefrom by the heating thereof, are not trapped, retained or confined for any substantial length of time in any one part of the entire boiler structure, nor in the feed-water heater, but are discharged therefrom substantially as fast as they are liberated from the feed-water, with the result that the life of all the sections of the boiler is greatly prolonged.

In water-tube boilers it is common practice to introduce the feed-water for the boiler directly into the economizer section, and unless the feed-water has been treated prior to its admission into the economizer section to expel the gases therefrom, those gases accumulate at the top of the economizer-section and remain there so long that they corrode the interior of the economizer. The gases are usually trapped in the upper drum of the economizer. One of the objects of this invention is to transfer heat from the economizer-section of a boiler to the feed-water pipe and to discharge the feed-water so heated directly into the steam-generating-section as distinguished from discharging it directly into the economizer-section so that the deleterious gases, dissolved in or carried by the feed-water immediately rise with the steam being generated in the steam-generating-section, to the top of the steam-generating-section of the boiler, whence they are discharged from the boiler with the steam substantially as fast as they are generated, with the result that the deleterious gases have no time or opportunity to remain long enough in contact with any particular part of the interior of the boiler to injuriously affect the boiler structure.

A further object of my invention is to maintain the water in the economizer-section at a considerably lower temperature than the temperature of the water in the steam-generating-section by transferring heat from the economizer-section to feed-water passing through the economizer-section in a coil or radiator located within said economizer-section, and to keep the level of the water in the economizer-section at any predetermined level by admitting thereto

water, freed from the deleterious gases, from the steam-generating-section of the boiler.

Other objects of my invention will appear in the specification and claims below. 60

In the drawings forming a part of this specification and in which the same reference characters are employed throughout the various views to designate the same parts, Fig. 1 is a vertical longitudinal sectional view of a water-tube boiler provided with my invention, the boiler structure being to a great extent diagrammatic and only such parts being indicated as directly cooperate with my invention; 65 70

Fig. 2 is another diagrammatic view of the automatic means for maintaining constant the height of level of water in the economizer-section of the boiler, for the purpose of illustrating how a boiler 75 equipped with my invention operates;

Fig. 3 is a view similar to Fig. 2 but showing the connections for manual, as distinguished from automatic, regulation of the supply of water to the economizer-section. 80

Referring first to the invention as illustrated in Fig. 1, the boiler-housing or casing A encloses the steam-generating-section B and the economizer-section C. The steam-generating-section B preferably comprises a triangular arrangement of drums, the top drum 1 being the steam-and-water drum, the next lower drum 2 being a water-drum, and the lowest drum 3 being the mud drum. 85 90 95 100 105 110

A bank of water tubes 4 extends in an inclined direction between the mud drum 3 and the water drum 2, a second bank of tubes 5 extends upwardly from the water drum 2 to the steam-and-water drum 1, and a third bank of tubes 6 extends between the steam drum 1 and the mud drum 3. Over the water drum 2 and at the top of the casing A is a header or steam drum 7 connected to the steam-and-water drum 1 by a bank of tubes 8 by means of which the steam in its passage from the steam-and-water drum 1 to the steam drum 7 may be superheated. The tubes 8 are in fact superheater tubes. Over the lower half of the bank of tubes 4 is an inclined baffle 9 and a vertical baffle 10 and the latter, entering the bank of tubes 5, extends forwardly toward the water drum 2. Over the forward end of the bank of tubes 5 is a baffle 11. Midway of the bank of tubes 6 and extending downwardly from the steam-and-water drum 1

is a baffle 12. Disposed between the bank of tubes 6 and the economizer C is a vertical baffle 13.

The hot gases of combustion rise from the fire-box 14 and travel longitudinally of the bank of tubes 4, directed by the inclined baffle 9, and then pass substantially vertically through said bank of tubes 4 and through the bank of tubes 5. They are then deflected 10 by the baffle 11 longitudinally of the bank 5 and into the space between the drums 1 and 7, and over and around the superheater tubes 8. Thence the gases pass downwardly through the bank of tubes 5 between the baffles 10 and 12, heating substantially one-half of the bank of tubes 6 in their downward passage. Passing around the lower end of the baffle 12 and through said bank of tubes, the gases then rise vertically between the baffle 12 and the baffle 13 where they enter the economizer-section C of the boiler. So far as has been above described, the boiler may be and is of usual construction.

25 The economizer-section C comprises an upper drum 15, a lower drum 16 and a bank of tubes 17 extending substantially vertically therebetween.

From the drum 15 I preferably provide a 30 baffle 18 extending downwardly vertically in the bank of tubes 17 so that the gases admitted to the economizer section 3 from the generating section B first pass downwardly between the baffle 18 and the baffle 13, then 35 through the bank of tubes 17, then vertically between the baffle 18 and the rear wall of the boiler housing A, and then out through the stack 5.

To supply feed-water to the boiler I provide a pipe 19 which may be provided with any suitable valve 20 to control, admit and check the water allowed to flow therethrough. This tube or pipe 19 passes through the wall of the upper economizer drum 15 and is connected to a coil or radiator 21 within the upper drum 15. The other end of the radiator 21 is connected to a pipe 22 which, passing downwardly from the upper economizer drum 15 is preferably connected to 45 and discharges into the lower drum 3. Connecting the steam-and-water drum 1 with the upper drum 15 of the economizer-section C is a pipe 23—23' in which is an automatic valve D which may be of any well known 50 automatic feed-water-regulating type. Its operation will be described more particularly below. The pipe 23 should enter the steam-and-water drum 1 below the water-level thereof, so that when the valve D is 55 open water from the steam-and-water drum 1 will flow into the upper drum 15 of the economizer-section C. Outside of the boiler structure A and adjacent and in front of the upper drum 15 of the economizer, is a gage-cock E, which may be of usual construction

provided with a sight-glass 24 by means of which the level of the water in the upper drum 15 of the economizer may be readily ascertained. The upper part of the gage-cock E is connected by a pipe 25 with a 70 space above the water level in the drum 15 and the lower end of the gage-cock is connected by a pipe 26 with the lower part of the drum 15 and in communication with the water therein. This common connection 75 makes the level of the water in the gage-cock the same as that in the drum 15.

Attached to the gage-cock is a regulator or controller F, the upper end of which is connected by a pipe 27 with the upper part 80 of the gage-cock E (and thus to the steam space in the drum 15), the lower end of which is similarly connected by a pipe 28 with the lower end of the gage-cock E (and thus with the water in the drum 15). 85

Referring now to Fig. 2 for a more detailed but somewhat diagrammatic view of the controller or regulator F and the valve D, the regulator F consists of the shell 29, preferably substantially cylindrical in shape, 90 having its upper end connected by the pipe 27 in any suitable way with the space above the water level in the drum 15 and its lower end connected by the pipe 28 with the water in the drum 15. Extending longitudinally 95 of the casing 29 is a tube 30 closed at its upper end and extending out through an end or side thereof where it is connected by a piping 31 to a closed casing 32 one side of which is covered by a diaphragm 33. 100

It will be seen from the above that as the level of the water in the drum 15 rises or lowers, it correspondingly respectively submerges or uncovers a greater or less length of the pipe 30 within the casing 29. This 105 pipe 30 is filled with a liquid which will volatilize and create pressure under the heat of the steam but which will become relatively cooler when covered with the water from the drum 15. It is to be remembered 110 that the water in the economizer, and consequently that in the casing 29, is kept relatively cool by the feed-water flowing therethrough as will be referred to again below. When, therefore, the water in the drum 15 115 falls below a predetermined point, more of the contents of the tube 30 is subjected to the heat of the steam, and pressure is created in the pipe 30. This pressure is communicated through the pipe 31 to the chamber 32 120 above the diaphragm 33 to depress the diaphragm and the parts operated thereby.

The valve D is preferably a nearly balanced valve. The construction is only diagrammatically illustrated in Fig. 2, because 125 no claim in this case is made to the particular construction of this regulating valve. It may be of any well known standard type and therefore a brief description will be all that is necessary for a full understanding of the 130

operation thereof in connection with applicant's invention. The diaphragm 33 which is carried by and securely attached to the cap or chamber 32, is also preferably secured to any suitable struts or frames 34, the lower end of which rests on and are secured to and are supported by the casing 35 of the automatic valve D. To the center of the diaphragm 33 is attached a stem 36 which, passing downward into and through the casing 35, carries with it a valve 37 and a valve 38 adapted to cooperate with the valve seats 39 and 40 respectively.

The stem 36 preferably extends below the valve 38 and out through the casing 35. Outside of the casing 35 it is provided with a disk or shoulder 41 against which bears the upper end of a coil spring 42, the lower end of which presses against a suitable rigid bracket or support 43 secured to the under side of the casing 35. From the above it is believed that it will be plain that when by reason of an increase of the pressure in the pipe 31, the diaphragm 33 is depressed, that movement of the diaphragm will force the valves 37 and 38 off their respective seats 39 and 40 and water from the drum 1 will pass through the valve, into the pipe 23' and into the upper drum 15 of the economizer-section. When the water has attained a predetermined height in the drum 15, and the tube 30 is covered with water, the pressure in the pipe 31 will fall, and the spring 42 will return the valves 37 and 38 to their respective seats to prevent any further passage of water from the drum 1 to the drum 15. The above then provides an automatic means for maintaining at substantially a fixed level the water in the upper drum of the economizer, the water being supplied thereto from time to time coming directly from the generator section of the boiler.

My invention is, however, not limited solely to the automatic replenishing of the economizer with water from the boiler. This may be accomplished manually because the evaporation of the water in the economizer is very slow under ordinary circumstances. Therefore it is only necessary for the engineer or boiler man to look from time to time at the sight-glass 24 and if he finds the water therein at a low level and if he observes that the level of the water in the drum 15 has fallen, he may manually open a hand valve and admit water from the steam-generator-section to the economizer. Such a modified construction is illustrated in Fig. 3 wherein the automatic valve D is replaced by a manually operable valve D'.

The above description has had reference merely to the conveying of feed water through a coil or radiator in the upper economizer-drum to the mud drum and the transfer of hot purified water from the steam-generating-section B to the econo-

mizer-section C through the pipes 23, 23'. Of course, the water will not fall in the economizer-section unless there has been an evaporation of it. When for any reason the heat of the water in the economizer-section is sufficient to generate steam (and generally speaking there are many installations in which the economizer will merely provide a means for heating the incoming feed-water without generating steam) and the pressure above the water level in the drum 15 is a little greater than it is in the boiler, such steam will pass from the drum 15 to the steam-and-water drum 1 through a check valve G and thence through the pipe 44 to the drum 1. This check valve may be of any ordinary and usual construction permitting of the flow of steam from the drum 15 to the drum 1 but preventing the backward flow of water from the drum 1 to the drum 15.

This feature of construction is important. The substantially continuous flow of cold feed-water through the coil 21 keeps the temperature of the water in the economizer-section C substantially lower than that of the water in the steam-generating-section B. But if, for any reason, the flow of feed-water should cease, then the temperature of the water in the economizer-section will rise and the said section C may become a steam-generating-section. The check valve G and pipe 44 permit the steam so generated in the economizer-section to be transferred to the main generating-section B whenever the pressure in the section C is substantially equal to that in section B. It will be apparent that, under these conditions, the valve D will be open for the free passage of water from section B to section C. When, however, the same conditions arise in the arrangement shown in Fig. 3, the fireman or boiler man will manually open the valve D' to keep the section C supplied with water from the section B.

Under some circumstances I may so design and proportion the parts of the boiler that the section B will be operative to generate steam at a relatively high temperature and pressure, and the section C will operate to generate steam at lower temperatures in which case the section C will be both an economizer-section and a steam-generating-section. In such an arrangement the steam, accumulating in the drum 15, will flow into the section B when the pressure in the section C has built up to the pressure in the section B. In this arrangement the regulator F will be so arranged, constructed and operated as to maintain the level of the water in the section C substantially constant by admitting thereto from time to time, through the valve D, water from the section B, as before described.

When the section C is arranged and is

operative to act merely as an economizer and not as a steam-generator, under normal conditions, that is to say, so long as cool feed-water is passing through the coil 21, the 5 water in the economizer remains substantially constant. As it circulates through the bank of tubes 17 between the drums 15 and 16 it is heated by the hot gases of combustion. In the drum 15 it is cooled by the 10 feed-water in the coil 21. The heat absorbed from the hot gases by the water in the section C is transferred to the feed-water passing therethrough. Under these conditions only a very small amount of water is required to be transferred thereto from section 15 B to maintain constant the level of the water in the drum 15.

The check valve G operates substantially like a safety valve in that by it the economizer-section is relieved of any accumulation of steam above a predetermined point of pressure. The accumulated steam, thus allowed to escape from the economizer-section, is not lost but is discharged into the steam-generating-section of the boiler. If, however, for any reason it is not deemed necessary or advisable to save or utilize the steam which may be so generated in the economizer-section, such steam may be allowed to 25 escape to the atmosphere through any other type of safety or pop valve construction.

When the operation of the boiler is such that the temperature of the water in the economizer-section is normally below steaming temperatures, as the result of the flow of cold feed-water through the pipe 19 and coil 20, the volume of the water in the economizer-section will remain substantially constant. The water therein will merely circulate without substantial evaporation and there will be no occasion to replenish the water in the economizer-section except at 35 long intervals. In such boilers only a little water is added at one time to that in the economizer-section and that is preferably drawn from the steam-generating-section or from any other convenient source. The volume of such added water will be so small that the volume of the deleterious or corrosive gases contained therein is substantially 40 negligible.

Having thus described my invention, I claim and desire to protect by Letters Patent of the United States:

55 1. The combination with a boiler comprising a steam-generating-section and an economizer-section having an upper drum, of means for freeing water of deleterious gases and for discharging said gases from the boiler substantially as rapidly as said gases are liberated from the feed-water, comprising a feed-water conduit passing through said drum of said economizer-section and discharging directly into said steam-generating-section, and means operative when the

supply of feed-water is substantially reduced and the steam pressure in said economizer-section is substantially that of the steam-generating-section of said boiler to transfer steam from said economizer section to said steam generating section and to deliver feed water to said economizer section from said steam generating section.

2. The combination with a boiler comprising a steam-generating-section and an economizer-section having a drum, of means for freeing feed-water of deleterious gases and for discharging said gases from the boiler substantially as rapidly as said gases are liberated from the feed-water, comprising a feed-water conduit passing through said economizer-section and discharging directly into said steam-generating-section, means to maintain substantially constant the level of the water in said economizer-section with water from said steam-generating-section, and means to transfer steam at and above boiler pressure from said economizer-section to said steam-generating-section, whereby any substantial reduction of the supply of feed water converts said economizer-section into a steam-generating-section and said economizer-section is not emptied of water.

3. In a boiler comprising a steam-generating-section and an economizer-section having an upper drum, the combination therewith of means to prevent the accumulation within the boiler of deleterious gases contained in the feed-water, comprising a feed-water conduit passing through said drum of said economizer-section and discharging into said steam-generating-section, means to supply said economizer-section with water from said steam-generating-section of said boiler and a connection between said economizer-section and said steam-generating-section, whereby steam at and above boiler pressure in said economizer-section is automatically carried over into said steam-generating-section whenever the supply of feed water is insufficient to maintain the temperature of the water in said economizer-section below boiling temperatures.

4. In a boiler comprising a steam-generating-section and an economizer-section, the combination of means to deliver feed-water directly to said steam-generating-section, means to pass said feed-water through the economizer-section to transfer heat from said economizer-section to said feed-water on its passage to said steam-generating-section of said boiler and to normally keep the temperature of the water in said economizer-section below steam-generating temperatures, means to keep said economizer-section supplied with purified water from said steam-generating-section of said boiler and means to transfer steam at boiler pressure from said economizer-section to said steam-generating-section when the flow of

feed-water through said feed-water pipe is retarded and the temperature of the water in said economizer-section rises to steam-generating temperatures.

5. In a steam boiler comprising a steam-generating-section and an economizer-section having upper and lower drums, the combination of a feed-water supply pipe, a coil in the upper drum of said economizer-section to one end of which said supply pipe is connected, a pipe connected to the opposite end of said coil and extending to and discharging into said steam-generating-section of said boiler, means to admit water 10 from said generator-section to said economizer-section, a conduit connecting the space above the water in the steam-generating-section with the space above the water in the said economizer-section, and a check 15 valve in said conduit operative to permit the flow of steam from said economizer-section to said steam-generating-section, and to prevent the flow of steam from said steam-generating-section to said economizer-section.

6. In a boiler comprising a steam-generating-section and an economizer-section, the combination therewith of means to deliver feed-water directly to said steam-generating-section, means to pass said feed-water through said economizer-section to transfer heat from said economizer-section to said feed-water on its passage to said steam-generating-section of said boiler and to normally keep the temperature of the water in said economizer-section below steam-generating temperatures, means to introduce water from the steam-generating-section of said boiler into said economizer-section to 20 compensate for any loss of water contained

in said economizer-section and automatic means to permit the escape of steam generated in the economizer-section of said boiler when the flow of feed-water is insufficient to keep the temperature of the 45 water in said economizer-section below boiling temperatures and the pressure of the steam in said economizer-section is substantially at boiler pressure.

7. In a boiler comprising a steam-generating-section and an economizer-section, the combination therewith of a feed-water pipe connected directly to said steam-generating-section, said pipe passing through said economizer-section to transfer heat from 50 said economizer-section to said feed-water on its passage to said generating-section and to normally keep the temperature of the water in said economizer-section below boiling temperatures, means to introduce water 55 from said steam-generating-section into said economizer section to compensate for any loss of water in said economizer-section, a pipe connecting the upper part of said economizer-section with the upper part 60 of said steam-generating-section, and a check-valve in said pipe to automatically permit transfer of steam generated in said economizer-section to said steam-generating-section through said pipe when the flow 65 of feed-water through said feed pipe is insufficient to maintain the temperature of the water in said economizer-section below steam-generating temperatures and the pressure of steam in said economizer-section 70 is substantially the same as that in said steam-generating-section. 75

In witness whereof, I have hereunto set my hand this 31st day of March, 1923.

JOSIAH H. ROHRER.
